TOY BEAR

Robert Zeidman, Mamaroneck, N. Y., assignor to Mail Pouch Tobacco Co., Wheeling, W. Va., a corporation of Delaware

Application March 19, 1957, Serial No. 45,332

Term of patent 3½ years

(Cl. D34—2)

Fig. 1.

Fig. 2.

Fig. 3.

I claim:

The ornamental design for a toy bear, substantially as shown.
